UNITED STATES PATENT OFFICE.

PAUL STONER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

SPEED-CHANGING DEVICE FOR GRINDING WHEELS.

Application filed November 18, 1920. Serial No. 424,902.

To all whom it may concern:

Be it known that I, PAUL STONER, a citizen of the United States, residing at Waynesboro, in the county of Franklin and State of Pennsylvania, have invented certain new and useful Improvements in Speed-Changing Devices for Grinding Wheels, of which the following is a specification.

My invention relates to a speed changing device for grinding wheels and provides means whereby the grinding wheel may be driven at a relatively low axial speed when first used, and at an increased speed when the wheel has become worn down.

One object of my invention is to provide the wheel spindle with a telescoping pulley adapted to run the spindle at different speeds, simple means being provided for changing from low to high speed.

Another object is to provide a safety device whereby the operator is prevented from driving a full sized wheel at high speed.

Referring to the accompanying drawings which are made a part hereof and on which similar reference characters indicate similar parts,

Figure 1 is a side elevation of a wheel spindle constructed in accordance with my invention with the telescoping pulley shown in section;

Figure 2, a plan view thereof with the casing broken away;

Figure 3, a section on line 3x3 of Figure 2; and

Figure 4, a detail section of the spindle.

In Figure 1, A represents the grinding wheel which is shown as having been worn down far enough to permit it to be operated at high speed without danger of breakage due to centrifugal force. A shield surrounding the said wheel is indicated at B and is adapted to be moved back as the wheel wears away, being secured in place by a clamp or the like after such adjustment. A casing C encloses the telescoping pulley and its associated parts.

The spindle 10 has mounted thereon a cylindrical belt receiving member 11 which is made secure thereto by means of a set screw 12 entering an aperture 13 in the spindle. This member 11 is crowned adjacent to one end, thus forming a pulley 14 to receive a belt 15 for imparting rotary motion thereto, while at the opposite end it is adapted to receive a sleeve 16 splined

thereto at 17 and crowned as at 18 to receive the belt 15 which climbs the inclined portion 19 when the sleeve is moved to overlie the pulley 14, as shown in Figure 4, and so imparts a slower speed to the spindle 10 and grinding wheel A. The sleeve 16 is also provided with an annular flange 20 which is spanned by a yoke 21 depending from a rack bar 22 slidably mounted within the casing C. The teeth of the rack bar 65 mesh with those of a segment 24 fastened to a vertical spindle 25 which is squared at its upper end as at 26 for the reception of a wrench or an operating handle of any suitable form. The spindle 25 is also provided adjacent the segment with a pinion 27 meshing with the teeth 28 of a safety locking bar 29 designed to strike against a lug 29^a on the shield B should the attendant attempt to operate a full sized wheel at the 70 higher speed.

The casing C or a movable portion thereof is provided with two depending lugs 30 which confine the belt both during the operation of changing the pulleys from the high 80 to the low speed, and vice versa.

Located within the cylindrical member 11 is a yieldable detent 31 designed to enter the annular groove 32 in sleeve 16 when the pulleys are set for high speed and to enter the 85 similar groove 33 when in the low speed position. Pins 34 secured to the machine frame or to the floor of the building are shown as passing through slots 35 to provide one conventional means for adjustment of the 90 casing B.

The operation of the device is as follows:

When the wheel A is of full size, it is not desired to have it travel at a very high speed owing to the centrifugal force created 95 therein, therefore when a large size wheel is in position, the shield B carrying the lug 29^a is in a forward position which places the lug 29^a in line with the safety bar 29. This prevents the shifting of the pulley sleeve 15 100 from the position shown in Figure 4, so that there is little or no danger of damage to the wheel A by reason of excessive speed. When the grinding wheel has become worn sufficiently the shield B must be moved back 105 to allow the work to contact with wheel A. The lug 29^a is now out of the path of the rod 29, and the vertical spindle 25 is rotated by means of a wrench or the like, which rotation causes the bar 29 to be projected be- 110

yond the lug 29^a and at the same time causes the withdrawal of the sleeve 16 to the position shown in Figures 1 and 2, which permits the belt to run on the smaller pulley 14 and impart a high speed to the wheel.

I do not propose to limit myself to the specific details shown and described, nor to the particular use I have made of my device, as it will be found useful in other relations

10 and in various modified forms such as will occur to those skilled in the art. The scope of my invention is shown by the appended claims.

Having thus fully described my said invention, what I claim as new and desire to secure by Letters Patent is:

1. In a grinding machine, a spindle, a grinding wheel secured thereto, a shield for the wheel, variable speed driving means on

20 the spindle, and means on the shield for controlling the operation of the speed varying means.

2. In a grinding machine, a grinding wheel, a speed changing driving means for the wheel, a rod moved by the change-speed devices, a shield for the wheel, and a lug on the shield in position to prevent movement of the rod the shield being adapted to be moved back as the wheel wears and 30 thus move the lug out of the path of the rod.

3. In combination, an expandible pulley comprising a belt receiving member and a belt receiving sleeve adapted to encircle the same or be withdrawn therefrom, a shaft adjacent the sleeve, connecting means between the shaft and the sleeve, a shield for the grinding wheel adapted to be moved as the wheel wears away, and means connected 40 to the shaft and restrained from movement by the shield in its first position, whereby movement of the sleeve is prevented.

4. In combination, a grinding wheel, driving means therefor comprising a pulley, an expansion sleeve for the same, and means to move the sleeve to encircle the pulley comprising a shaft extending transversely to the pulley and adapted to be rotated, connecting means between the shaft and the

50 sleeve, a slideable rod connected to the shaft, and a shield for the wheel having a portion normally in position to prevent movement of the rod, but adapted to be moved out of its path as the wheel diminishes in size.

55 5. In a grinding machine, a casing, a shaft therein, a belt pulley on the shaft, a sleeve at one end of the pulley adapted to slide under the belt to change the speed of

the shaft, a slideable toothed shifter bar for the belt, a second toothed slideable bar projecting at one end from the casing, a shaft having a squared head projecting from the casing, rack segments on the shaft engaging said toothed bars, and means outside the casing adapted to engage the second bar to prevent operation of the speed changing means, substantially as set forth.

6. The combination of an abrading device, means for driving the same, speed changing means including a movable element, and 70 means to prevent increase of speed of the abrading device until the same has worn down to a predetermined extent said last-named means including an obstruction directly in the path of said element of the 75 speed-changing means, substantially as set forth.

7. The combination of a rotary grinding wheel, speed-changing driving means therefor including a reciprocatory part, and 80 means to prevent change to higher speed including an obstruction maintained directly in the way of the reciprocatory part by said wheel so long as the wheel is above a predetermined diameter.

8. In a grinding machine, a grinding wheel, change-speed driving means for the wheel, a rod positioned to be moved by said means in their speed-changing movement, and a shield for the wheel adapted to be 90 positioned to either prevent or permit movement of said rod, substantially as set forth.

9. In a grinding machine, a grinding wheel, change-speed driving means for the wheel, a rod positioned to be moved by said 95 means in their speed-changing movement, and a stop for the wheel adapted to be positioned to either prevent or permit movement of said rod according to the size of the wheel, substantially as set forth.

10. In a grinding machine, a grinding wheel, a spindle for driving it, speed-changing driving means for the spindle, and a shield for the grinding wheel adjustable to permit or prevent speed-changing movement of said means according to the size of the wheel, substantially as set forth.

In witness whereof, I have hereunto set my hand and seal at Washington, District of Columbia, this thirteenth day of November, 110 A. D. nineteen hundred and twenty.

PAUL STONER.
